US00D840223S

(12) **United States Design Patent** (10) **Patent No.:** **US D840,223 S**
(45) **Date of Patent:** **** Feb. 12, 2019**

(54) **PIERCER FOR BEVERAGE INGREDIENT CARTRIDGE OR POD OR THE LIKE**

(71) Applicant: **PepsiCo, Inc.**, Purchase, NY (US)

(72) Inventors: **Carlos Hernan Marina**, Deerfield Beach, FL (US); **Hernán Javier Giorgi**, Buenos Aires (AR); **Dario Federico Stanziano**, Buenos Aires (AR)

(73) Assignee: **PepsiCo, Inc.**, Purchase, NY (US)

(**) Term: **15 Years**

(21) Appl. No.: **29/641,118**

(22) Filed: **Mar. 20, 2018**

Related U.S. Application Data

(63) Continuation of application No. 29/580,884, filed on Oct. 13, 2016, now Pat. No. Des. 815,942.

CLAIM

The ornamental design for a piercer for beverage ingredient cartridge or pod or the like, as shown and described.

DESCRIPTION

FIG. 1 is a top front perspective view of a piercer for beverage ingredient cartridge or pod or the like showing the claimed design in an environment in which it may be used; FIG. 2 is another top front perspective view thereof;

FIG. 3 is a bottom rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the figures show portions of the piercer for beverage ingredient cartridge or pod or the like that form no part of the claimed design.
